Primary Examiner — Khawaja Anwar*Assistant Examiner* — Taylor O Mortorff(74) *Attorney, Agent, or Firm* — Banner & Witcoff, Ltd.(57) **CLAIM**

The ornamental design for an articulating arm as shown and described.

DESCRIPTION

FIG. 1 is a front, left perspective view of an articulating arm showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front, left perspective view of an articulating arm shown in an exemplary environment.

The broken lines depicting the remainder of the articulating arm form no part of the claimed design.
